UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed May 31, 1924. Serial No. 717,009.

To all whom it may concern:

Be it known that I, CLARENCE M. CREWS, a citizen of the United States, residing in Brooklyn Borough, in the county of Kings, 5 city and State of New York, have invented certain new and useful Improvements in Typewriting Machines, of which the following is a specification.

This invention relates to typewriting of 10 the class known as continuous billing, in which class of work a multiple ply continuous work-web is interleaved ordinarily with carbons mounted on a carbon-carrier that is advanceable toward the typewriter 15 platen at typing, and retractable upon displacement of the platen to shift the carbons from a typed work form to a fresh work form on the web, when desired.

It is an object of the present invention 20 to provide a machine for doing this class of work, in which the displacing of the platen is obviated, and the carbon-carrier is eliminated altogether. It is a further object to provide a machine for this purpose 25 which is economical to manufacture and which is derivable from an ordinary correspondence typewriting machine by the addition of a simple attachment thereto.

To this end use is made of discrete carbons of substantially greater width than 30 the work-web, which are preferably interleaved with the work-web, in such manner that both side margins of the carbons protrude beyond the sides of the work-web. 35 These unattached carbons are fed forward and backward around the platen, with the work-web, by means of the usual feed-rolls running on the platen. When it is desired to shift the carbons from a typed section of 40 the web to an untyped section thereof, the work-web and carbons are first fed together to position the carbons clear of the platen where they may be straightened. The discrete carbons are then clamped independ- 45 ently of the work-web, by their protruding margins at or near their edges remote from the platen, and held stationary in this carbon-shifting position while the work-web is fed relatively to them until the desired relative shift has been accomplished. The carbon clamps are then released, and the carbons are fed with the work-web to typing 50 position.

It is desirable in this mode of operation 55 that the carbon-shifting position of the car-

bons be at the front of the platen, so that the carbons may be visible to the operator when the relative shift is being effected, in order that they may be accurately located with reference to the clamps, and that the correct amount of relative shift may be determined by observation of the carbons and the work-web. It is also desired to utilize the platen to draw the work-web between the clamped carbons. The work-web therefore, 60 is not led into the rear of the machine from the source of supply, as usual, but is led to the platen, bottom end first, over a high paper-table at the front thereof, so that it may be caused to pass from front to rear 65 when shifted relatively to the carbons. The work-web is thus caused to progress through the machine from front to rear by relative shifting and the carbons are caused to progress from the bottom toward the top of the 70 web between the writing of successive bills.

Provision is made at the delivery side of the platen, that is to say, at the rear of the platen in this machine, of means for severing the type web-sections. Since the severing of the web at the rear of the platen by a tearing-off knife of the usual construction would be awkward because of the obstruction formed by the front paper-table, novel web-severing means are provided. Such 80 web-severing means includes a chopping knife, mounted upon a co-operating shearing block adjustable toward and from the platen to accord with different lengths of bill-forms. In order to neutralize the forces 85 acting transversely of the rear paper-table and thus prevent undue strain upon the carriage guiding and supporting means when the knife is operated to chop off a web-section, a handle is provided which is operable in the plane of the rear paper-table and which is connected, through a suitable cam, to move the chopping blade transversely of 90 said table when so operated.

Other features and advantages will hereinafter appear.

In the accompanying drawings,

Figure 1 is a front elevation of a type-writing machine having the present improvements applied thereto, an intermediate portion of the machine being cut away.

Figure 2 is a fragmentary detail view partly in section of the upper end of the front paper-table, showing the clamps applied to the margins of the carbon-sheets to hold

them stationary for relative work-web and carbon shifting.

Figure 3 is a detail sectional view on the line 3—3 of Figure 2, showing one of the side guides for the continuous work-web.

Figure 4 is sectional side elevation of the invention and so much of the old mechanism as is necessary to an understanding thereof. In this view the clamps are shown ineffective 10 and the carbons are shown in carbon-shifting position.

Figure 5 is a sectional plan view on the line 5—5 of Figure 7, showing details of construction of the web-severing means.

15 Figure 6 is a transverse vertical section on the line 6—6 of Figure 5, showing the arrangement of the knife and the shearing block.

Figure 7 is a sectional front elevation 20 showing the web-severing means.

Figure 8 is a front elevation similar to Figure 1, but on a smaller scale, of a form of the invention designed for use with a fan-fold work-web.

25 Figure 9 is a side elevation, partly in section, of the mechanism shown in Figure 8.

Figure 10 is a sectional view, taken on the line 10—10 of Figure 4, looking in the direction of the arrows.

30 Figure 11 is a sectional view on the line 11—11 of Figure 8, looking in the direction of the arrows.

The typewriting machine comprises a cylindrical platen 10 journaled by its axle 11 35 in a platen-frame 12, which is mounted to travel in letter feed and return directions in the usual manner. Feed-rolls 13 co-operate with the platen 10 to feed the work-web 14 and interleaved carbons 15 in line-space and reverse directions around the platen.

40 As has been stated, the plies of the work-web 14 are interleaved with carbons 15 of substantially greater width than themselves, 45 the carbons being preferably arranged to have their side margins protrude beyond both side edges of the work-web. (See Figure 1.) The work-web 14 is led into the machine, bottom end first, over a high skeletonized paper-table 16 at the front of the platen, which is supported by means of brackets 17 on the ends 18 of the platen-frame 12. Side guides 19 on the front paper-table 16 may co-operate with the side 50 edges of the carbons 15 to keep the carbons true and in register, and side-edge guides or gages 20 secured to the paper-table 16 near its upper end by set screws 21 assist in controlling the work-web 14 in the machine. 55 These side-edge gages 20 are adjustable laterally of the front paper-table 16 along a slot 22 that extends from side to side of the table.

60 In starting the work, the carbons 15 are properly interleaved with the second form-

section from the lower end of the web, which end of the web is then introduced downwardly at the front of the platen and drawn backwardly to first writing-line position by the aid of a separate sheet inserted temporarily into the machine from the rear to form a front-insertion guide. The typing of said second form-section is then effected, the web 14 and carbons 15 being line-fed together by the platen 10 and co-operating feed-rolls 13 while this is in progress.

At the conclusion of typing said form-section, the platen is rotated by one of the platen-turning knobs 23 to advance the work-web 14 and carbons 15 together until 60 the carbons occupy a position on the front paper-table 16 where they are straight and entirely free of the platen, as shown in Figure 4. The carbons 15 are then clamped stationary at their upper corners by clamps 24 which are fast on a rod 25 and which are located beyond the bounds of the work-web 14. The rod 25 is provided with an operating handle 26 for the clamps 24, which may be detained in position to maintain the 65 clamps either effective or ineffective by a double-acting spring 27 connected to the handle 26 and to the paper-table 16 to cross the axis of the rod 25 in the movements of the handle between the full-line clamping 70 position and the dot-and-dash non-clamping position of Figure 2.

After the clamps 24 have been applied to hold the carbons 15 stationary, the platen is rotated backwardly by one of the platen-turning knobs 23 to shift the work-web 14 relatively to the carbons 15 a distance of one 75 form length. Each carbon may have a strip of paper 28 pasted along its upper margin to reinforce said margin and guard it against 80 injury by the work-web at the shifting operation.

85 At the completion of the relative shifting, the line of division between the typed web-section and the end section on the web, which 90 received no typing, is in register with a chopping knife 29 mounted behind the platen. This knife 29 and its operating means will be described in detail presently. The end section of the web is next severed by 95 the knife and the clamps 24 are released, whereupon the platen is again rotated backwardly by one of the platen-turning knobs 23 to feed the carbons and the fresh web-section with which they have become interleaved as a result of the relative shifting, 100 down to first writing-line position. The cycle of operations is thus completed and will be repeated with reference to the fresh web-section and the succeeding web-sections 105 in turn. It will be noticed that each web-section, when typed, is permitted to remain on the web until the succeeding section has 110 been typed and the carbons have been stripped therefrom.

The web-severing knife 29 is pivotally mounted upon a shearing block 30 to move across the face thereof, the shearing block in turn being carried by brackets 31 extending rearwardly and upwardly from the sides of the platen-frame 12 in the plane of a usual rear paper-table or shelf 32. The shearing block 30 is held in adjusted position upon these brackets 31 by set-screws 33. In 10 addition to the knife 29, the shearing block carries a cam 34 mounted for rotation about a pivot 35 that extends at right angles to the plane of the rear paper-table. This cam 34 has a cam path 35a in which a projection 36 on the chopping knife 29 rides. The arrangement is such that a handle 37 on the cam may be actuated by movement in the plane of the rear paper-table 32 to move the chopping knife 29 transversely thereof. 15 20 to shear the work-web 14. This operating means for the knife, guards the knife supports and the carriage guides and supports against injury which would result if the chopping knife were arranged to be actuated by a blow in a direction transverse to the rear paper-table. The knife, as shown, will engage the webs and sever them across their entire width substantially instantaneously. It will be appreciated, however, that by a 25 30 slight alteration of the design a scissors-like operation could be obtained. The knife is held toward the shearing block by a spring 39 interposed between the knife 29 and an adjustable nut 40 on the pivot-pin 41 of the 35 knife. The adjustable nut 40 may be locked to preserve the desired degree of stress upon the spring by means of a lock-nut.

At the time when the carbons 15 are moved from their Figure 4 position down to 40 writing position, the lower edges of their protruding margins might catch upon the forward edge of the usual paper-apron 42 if provision were not made to guard against this. Fingers 43 are accordingly provided 45 to extend down from the sides of the front paper-table to points between the paper-apron 42 and the platen 10. These fingers 43 guide the carbons 15 beneath the paper-apron and guard them from mutilation by 50 the paper-apron.

In Figures 8 and 9, there is shown another form of the invention particularly adapted for work with a fan-fold web. This form is generally similar to the form previously 55 described. Each carbon 44, however, is of necessity terminated within a fold of the fan-fold web at one side, and each, therefore, has only one protruding margin whereby it may be clamped. The carbons 60 44 are stiffened somewhat by strips of paper 45 pasted to their backs along their upper margins and along their protruding side margins to assist in preventing displacement of the carbons at shifting. Clamps 46 65 are arranged to extend along substantially

the entire length of the carbon-sheets 44, and are controlled in their movement, in such manner, that they are always parallel to the front paper-table 16. The clamps 46 are mounted at their lower and upper 70 ends respectively on parallel links 47 and 48 of equal length, fast on shafts 49 and 50, which shafts have parallel operating arms 51 and 52 of equal length connected by a link 53. The right-hand arm 52 on the upper shaft 50 75 is extended beyond its connection with the link 53 and provided with a handle 54 whereby the clamp may be moved between its effective and ineffective positions. A double-acting spring 56 controls the clamps 46 to 80 maintain them either effective or ineffective as desired. The operation of this form of the invention is the same as that of the form previously described.

In either form of the invention the protruding-side margins of the carbons may be secured to each other if desired.

It is a point that the knife supporting brackets 31 and the front paper-table brackets 17 extend from common bases 57 and 90 that both are secured to the machine simultaneously by the turning home of screws 58 and 59 to fasten said bases to the ends 18 of the platen frame. All of the novel mechanism, therefore, is combined in a unitary 95 attachment which can be quickly applied to convert a standard machine into a continuous biller.

The elimination of the carbon-carrier besides saving the cost of this member and 100 operating mechanism therefor, makes unnecessary the provision of a long track for the carbon-carrier, and this, in turn, obviates the need of a frame extension and additional guides to support the track. 105

Variations may be resorted to within the scope of the invention, and portions of the improvements may be used without others.

Having thus described my invention, I 110 claim:

1. In a continuous billing typewriting machine for use with a set of carbons, the combination with a cylindrical platen, of a front paper-table over which a work-web may be guided from a source of supply 115 downward to the platen at the front thereof, the paper-table being longer than the carbons, means at the upper end of the paper-table for clamping the carbons stationary while the work-web is fed backward by the platen to effect a relative shifting of the work-web and carbons, and means at the rear of the platen to sever the work-web.

2. In a continuous billing typewriting machine for use with a set of carbons, the combination with a cylindrical platen, of a paper-table over which a work-web may be guided from a source of supply to the platen, the paper-table being longer than 120 the carbons, means at the end of the paper- 125

table remote from the platen for clamping the carbons by their outer ends to hold them stationary while the work-web is fed by the platen to effect a relative shifting of the work-web and carbons, and side guides for the work-web beyond the clamping means, and therefore beyond the travel of the carbons, to guide the work-web between the carbon-clamping means so that it will not be clamped with the carbons.

3. In a continuous billing typewriting machine for use with a set of carbons, the combination with a cylindrical platen, of a front paper-table over which a work-web narrower than the carbons may be guided from a source of supply downward to the platen at the front thereof, the paper-table being longer than the carbons, means at the upper end of the paper-table for clamping the carbons stationary while the work-web is fed backward by the platen to effect a relative shifting of the work-web and carbons, side guides for the work-web to guide it clear of the carbon-clamping means to avoid being clamped thereby, and means for adjusting the web-side guides laterally of the paper-table, the web-side guides being located above the clamping means and therefore above the range of travel of the carbons where they cannot obstruct the travel of the carbons, however adjusted.

4. In a continuous billing typewriting machine for use with a set of carbons, the combination with a cylindrical platen, of a front paper-table over which a work-web narrower than the carbons may be guided from a source of supply downward to the platen at the front thereof, the paper-table being longer than the carbons, a pair of clamps at the upper end of the paper-table for clamping the side margins of the carbons, but not the work-web, to hold the carbons stationary while the work-web is fed backward by the platen to effect a relative shifting of the work-web and carbons, means common to said clamps for operating them, and means to detain the clamps in effective or ineffective condition.

5. In a continuous billing typewriting machine for use with a set of carbons, the combination with a cylindrical platen, of a paper-table over which a work-web narrower than the carbons may be guided from a source of supply to the platen, the paper-table being longer than the carbons, means at the end of the paper-table remote from the platen for clamping the side margins of the carbons, but not the work-web, to hold the carbons stationary while the work-web is fed to effect a relative shifting of the work-web and carbons, and means to sever the work-web.

6. In a continuous billing typewriting machine for use with a set of carbons, the combination with a cylindrical platen, of

a paper-table over which a work-web narrower than the carbons may be guided from a source of supply to the platen, the paper-table being longer than the carbons, a pair of clamps at the end of the paper-table remote from the platen for clamping the side margins of the carbons, but not the work-web, to hold the carbons stationary while the work-web is fed to effect a relative shifting of the work-web and carbons, a rod extending across the paper-table on which the clamps are fast, a handle for rocking the rod to move the clamps between effective and ineffective positions, and a double-acting spring connected to the handle to hold the clamps in either of said positions.

7. In a continuous billing typewriting machine for use with a set of carbons, the combination with a cylindrical platen, of means for clamping the side margins of the carbons, but not the work-web, to detain the carbons stationary in a carbon-shifting position at the front of the platen while the work-web is fed in the machine to accomplish a relative shifting between the work-web and the carbons following the typing of a form-section, a paper-apron adjacent the platen, and front-insertion guide-fingers overlying the side margins of the carbons and extending down between the paper-apron and the platen to prevent snagging of the lower edges of said side margins of the carbons upon the paper-apron when the carbons are fed from carbon-shifting position down to writing position.

8. In a continuous billing typewriting machine for use with a set of carbons, the combination with a cylindrical platen, of means for effecting a relative shifting of the carbons and an interleaved work-web, and web-severing means comprising a shearing block and a pivoted knife to cooperate therewith.

9. In a continuous billing typewriting machine for use with a set of carbons, the combination with a cylindrical platen, of means for effecting a relative shifting of the carbons and an interleaved work-web, a table for guiding the work-web away from the platen at the delivery side thereof, a chopping knife movable transversely of the table to sever the web, and operating means for the knife comprising a handle movable substantially parallel to the table.

10. In a typewriting machine, the combination with a cylindrical platen, of means for conducting a work-web to the platen from the front thereof, and a knife at the rear of the platen to sever the web.

11. In a continuous billing typewriting machine, the combination with a cylindrical platen, of brackets extending outward from the platen at the delivery side thereof, a shearing block adjustable along the brackets toward and from the platen, and a chopping

knife mounted upon the shearing block for co-operation therewith to sever the work-web.

12. In a continuous billing typewriting machine, the combination with a cylindrical platen, of brackets extending outward from the platen at the delivery side thereof, a shearing block adjustable along the brackets toward and from the platen, a chopping knife mounted on the shearing block for movement transversely of the plane of the brackets to sever a work-web, a handle pivoted on the shearing block for movement substantially parallel to the plane of the brackets, and operating connections from the handle to the chopping knife.

13. The combination with a standard correspondence typewriting machine, of a unitary attachment to convert said machine for continuous billing, consisting of a pair of base-members attached to the ends of the platen-frame of the machine, two pairs of brackets on the base-members, means supported at the introductory side of the platen by one of the pairs of brackets to support a set of carbons in a straight condition free of the platen and hold them stationary while an interleaved work-web is shifted relatively to them, and web-severing means supported at the delivery side of the platen by the other pair of brackets.

14. In a continuous billing typewriting machine for typing upon a multiple ply fan-fold work-web, by means of a set of carbons wider than the work-web, the combination with a cylindrical platen, of means for guiding the work-web and carbons so that each carbon will protrude at one of its side margins beyond the side of the work-web, and means for clamping the carbons by their protruding margins throughout substantially the entire length thereof to hold the carbons stationary during shifting of the work-web relatively to them, and to prevent skewing of the carbons during such relative shifting.

15. In a continuous billing typewriting machine for typing upon a multiple ply fan-fold work-web, by means of a set of carbons

wider than the work-web, the combination with a cylindrical platen, of means for guiding the work-web and carbons so that each carbon will protrude at one of its side margins beyond the side of the work-web, means for clamping the carbons by their protruding side margins, and a re-enforcing and stiffening strip on the side margin of each carbon to co-operate with the carbon-side-guiding means and with the clamping means to prevent skewing of the carbons when the work-web is shifted relatively to them.

16. In a continuous billing typewriting machine for typing upon a multiple ply fan-fold work-web, by means of a set of carbons wider than the work-web, the combination with a cylindrical platen, of means for guiding the work-web and the carbons so that each carbon will protrude at one of its side margins beyond the side of the work-web, a paper-table to support the work-web and carbons in carbon-shifting position, and means to hold the carbons by their protruding side margins throughout substantially the entire length thereof, comprising a pair of clamps to overlie said side margins, and means common to the clamps, constructed to move them toward and from the paper-table simultaneously, while maintaining them always parallel to the paper-table.

17. In a continuous billing typewriting machine for use with a set of carbons, the combination with a cylindrical platen, of a carbon-shifting table, means for guiding the carbons and interleaved work-web to cause a side margin of each carbon to protrude beyond the side of the work-web, a clamp to clamp the protruding side margins of said carbons in carbon-shifting position while the work-web is shifted relatively to the carbons, the clamp extending for a substantial distance in the direction of the length of the carbons, and operating means for the clamp to move it between effective and ineffective positions, and constructed to maintain the clamp always parallel to the carbon-shifting table.

CLARENCE M. CREWS.
